UNITED STATES PATENT OFFICE.

FRED ZIMMERMAN, JR., OF CLEVELAND, OHIO.

PICTURE FRAME AND METHOD OF PRODUCING THE SAME.

Application filed February 2, 1924. Serial No. 690,326.

My invention relates to an improvement in picture frames and a method of producing the same, and in general my object is to provide a jointed frame in which the joints or miters are embellished and ornamented in a simple and inexpensive way in exact simulation of any desired artistic design carved or tooled in intaglio and relief.

A hand carved or tooled frame possesses inherent ornamental qualities and a richness of appearance exceedingly difficult to duplicate in an inexpensive way in manufacturing wooden picture frames in a large commercial way. Close simulations to carve or tool frames have been produced but in creating such frames the joints and miters present certain obstacles to the production of good and accurate reproductions of artistic designs in intaglio and relief except at comparatively high or prohibitory costs. One common method is to produce a desired design in a straight piece of molding and then join or miter sections of this molding together in making a picture frame, and in so doing the cut portions of the design must be carefully cut and skillfully matched at a high cost of labor and with loss or waste of materials, and moreover, many desirable and attractive designs cannot be cut and matched in that way for quantity reproduction. Another old method in general use involves the joining or mitering of separate pieces of prepared molding into a picture frame and the application of separate embossed pieces made of plastic substances or other materials to cover and conceal the joints. Such added pieces build up the frame and make it thicker or high at the joint, or if a hollow relief effect is desired the body of the frame at the joint must be made thinner and weaker. In this connection it must be understood that a given size, style or pattern of a picture frame may demand a molding of very small cross section which will not permit a material reduction or removal of the stock at the joint and a perfect or exact simulation of deep carving or tooling by the common methods described. Many other conditions and requirements must be met which make it difficult or expensive to produce satisfactory ornamental patterns and designs in in-

taglio or hollow relief in the wood itself across the joints or miters without weakening or distorting the same, but my present method permits an endless variety of bold and beautiful patterns or designs to be made in intaglio or hollow relief in the molding itself at and across the joints or miters after the molding sections have been united, without injury to the same and with a minimum of expense and in a single rapid operation, all as hereinafter shown and described and more particularly pointed out in the claims.

In the accompanying drawings, Fig. 1 is a sectional view of a part of a hot press used in practicing my method of producing ornamental picture frames. Fig. 2 is a top view of the bed plate or platen of the press with a mitered part of a picture frame in place thereon to receive an impression. Fig. 3 is an enlarged sectional view of the mitered joint of the picture frame on line 3—3 of Fig. 2, showing the burning die in action. Fig. 4 is a perspective view of an angular burning die. Fig. 5 is an elevation of one corner of a picture frame embellished across its mitered joint according to my invention, and Figure 6 is a cross section thereof on line 6—6 of Figure 5. Figure 7 is an elevation of mitered corner showing a different pattern or design, and Figure 8 is a cross section and edge elevation of this modified form of frame on line 8—8 of Figure 7.

In producing a picture frame according to my invention, a rabbeted strip of wood of any desired pattern or shape in cross section is cut into given lengths and preferably with a mitered cut to permit the pieces to be matched together on a line bisecting the angle of junction. The molding may be plain, or it may possess an embossed or ornamented surface. To obtain the latter, I may produce a stippled or corrugated or other irregular pattern on the front face of a plain molding by feeding a straight strip of wood molding between two rotary dies or wheels heated to a burning temperature to effect burning and an impression of the desired design in the face of the wood. This facial embellishment or ornamentation may then be changed or altered in part by the succeeding steps hereinafter

described to produce a pleasing and attractive composite design or pattern, especially at the mitered corners of the frame.

Thus in carrying on the method, the cut 5 pieces of molding, whether plain or ornamented, are nailed and glued together to produce a complete picture frame, for example a square or rectangular open frame in which each corner is mitered and permanently 10 united together. The joining of such mitered frames is a hand operation carried on in most shops by skilled and experienced workmen who are relied upon to make perfectly matched joints and unions, but the warped 15 condition of a piece of wood may produce a poor joint or make matching and a good joint difficult or impossible. In general, the aim is to make a perfect joint and at this stage of the proceedings the frame is a complete 20 frame with solidly united joints, and the front surface may now be finished or embellished further.

As indicated at the beginning, especially 25 distinctive and pleasing picture frames are produced by carving or tooling suitable designs in intaglio or hollow relief upon the front of the mitered corners. This is a slow and expensive operation, and in lieu thereof I simulate such carvings by subjecting the 30 mitered corners to heat and pressure, applying both concurrently across the mitered joint without injuring the completed joint, and in so doing also obliterate or conceal the line of union, and also correct or remove 35 any imperfections made in joining the parts together, all in a single simple operation.

Thus, as a preliminary, I make a flat metal 40 die 2 of angular shape corresponding to the angular corner of the mitered frame F, the working face of the die being formed on lines conforming in the main to the profile of the molding to be treated and having sharply cut ridges, teeth, points, etc., therein forming prominent or essential relief 45 portions 3 which may be of any desired design or pattern, wherewith an impression may be made to give the desired intaglio or carved effect in the molding.

However, the molding is made of wood, 50 which may split easily, and the moldings also vary in shape and form and have sharply defined corners; and in many instances the molding is thin, small in cross section, and fragile. Moreover, the design or pattern to be produced is also intended to include and span the finished mitered joint, which of course must not be riven asunder, destroyed or impaired. Therefore, in using die 2, I attach the same to the bottom plate 4 of a reciprocal plunger or piston 5 of a power operated press, and heat the plate 4 and die 2 throughout operations by means of a gas burner 6 or by any other suitable heating device or element capable of keeping the sharp points or relief portions 3 of the die

at an even temperature whereby burning or charring of the wood may be rapidly effected as pressure is applied and the die is forced downward upon the molding. In this operation the mitered corner of frame F is seated 70 flat upon the bed plate 6' of the press immediately beneath and in register with the angular die 2 and held within an angular pocket formed by a centering stop and backing plate 7 fixed to bed plate 6'. The two 75 pieces of molding are backed at their outer edges by the straight inner edges 8 of centering plate 7, so that the mitered or joint line 9 between the two pieces of molding can not open under the pressure of the die from 80 above. Furthermore, the mitered joint cannot spread apart or open because the design or pattern comprises complementary sharp 85 relief portions 3 in the die on opposite sides of the mitered line which act together to lock the two mitered pieces in definitely 90 fixed relation from the beginning to the end of the combined burning and impressing operation. The die moves slowly or at a 95 pace in keeping with the burning operation, and does not stop necessarily when the full profile of the molding is engaged by the major surface of the die cavity; that is, it may and in some patterns or designs is 100 designed to carry on and burn and impress itself deeper into the wood until a marked intaglio effect involving the entire corner surface of the frame is produced. The operation consumes only a few seconds, and the upward movement of the die instantly 105 separates the die from the molding. The forming of the desired pattern across the mitered joint is now finished, leaving the joint itself in the same perfect state of union as at the beginning. The same operation is 110 then repeated on the remaining corners of the picture frame, wherupon any desired painting, coating, gilding or other finishing step may be taken. The browned or burned surfaces produced by the die are of superficial depth, but are completely covered and concealed by the materials applied in finishing and decorating. The finished product 115 possesses all the characteristics and the same attractiveness of appearance as the more expensive hand carved or tooled frames when coated, gilded and finished, but the work is expedited, labor is lessened, the cost greatly reduced, and the finest designs and patterns 120 may be reproduced perfectly on an extensive commercial scale. In Fig. 2, two nailed mitered pieces are shown seated within the angle plate 7, but these pieces may be placed in mitered abutting relation within the angle 125 and subjected to the pressure and heat of the ornamenting die and subsequently nailed or glued together, if desired. Thus, in either case if the separate mitered pieces do not match exactly in profile at their abutting edges the hot impression of the die will cor- 130

rect any fault and make a perfectly matched profile across the joint along the entire line of union.

What I regard as my invention and discovery, and desire to claim, is:

1. A method of producing ornamental picture frames, consisting in joining separate pieces of picture molding, and subsequently pressing an ornamenting die heated to a burning temperature across the joint and into the surface of the frame with equal pressure at each side of the joint until a pattern in hollow relief is produced.
2. A method of ornamenting a jointed picture frame, consisting in placing an ornamenting die in a spanning position across a joint in the frame; in heating the die to a burning temperature; and in pressing the heated die into the face of the frame with equal pressure at opposite sides of the joint simultaneously.
3. A method of ornamenting a mitered picture frame, consisting in placing separate pieces of picture molding in mitered relation, and then forming an ornamental impression in the face of the frame across the miter joint by the simultaneous application of heat and pressure, the pressure being applied equally at each side of the joint while the mitered pieces are being rigidly held from spreading apart.
4. A method of ornamenting a mitered picture frame, consisting in placing an angular die upon the corner portions of the mitered picture frame and pressing said die into the face of the frame across the mitered

joint under a burning temperature, the duration of application of pressure and heat being limited to burn the surface engaged to only a superficial depth.

5. A method of producing an angular picture frame, consisting in arranging separate pieces of picture molding in mitered union; in placing the mitered corners of the frame in register with an angular ornamenting die; heating the die; and in pressing the heated die into the surface of the frame at each side of the mitered joint and including the joint until an ornamental pattern in hollow relief is obtained, the lines of pressure being directed to lock the two mitered pieces in definitely fixed relation from the beginning to the end of the burning and impressing operation.

6. A method of producing an angular picture frame, consisting in mitering separate pieces of picture molding and abutting the same together; in placing a mitered corner of the frame within an angular backing member in register with an angular die; in heating said die to a burning temperature; and in pressing the heated die against the face of the mitered corner of the frame and the mitered joint until the ornamental pattern of the die is reproduced therein, while preventing lateral movement and spreading apart of the mitered pieces by said angular backing member.

In testimony whereof I affix my signature.

FRED ZIMMERMAN, JR.
